AUTOMATIC TURRET GRINDING OR
POLISHING MACHINE

Gustave A. Carlson, Detroit, Mich.

Application October 14, 1943, Serial No. 506,131

10 Claims. (Cl. 51—53)

This invention relates to automatic turret grinding or polishing machines particularly designed for, what is known in shop parlance, as a special purpose machine, although as will appear more fully hereinafter, the machine of the present invention is capable of other uses.

The present machine is particularly designed for removing the sharp edged burr formed at the line of juncture between the bore and the outer curved face of a special purpose washer which forms a part of a precision job, the bore, after the washer has been hardened, being lapped to accurate dimension after which the outer curved face of the washer is ground to exact size, to form a smooth highly polished, finished surface. The grinding of the outer curved face of the washer after the lapping of the bore thereof, tends to form a very sharp knife-like edge, or burr, at the line of juncture between the curved outer face of the washer and the bore which it is necessary to remove. Removal of this burr which has heretofore always been performed by hand, is effected by the use of a flat disk of abrasive cloth, or paper, clamped at the end of a suitable fixture which is rotated and thrust into the bore of the washer so as to cause the flexible disk of abrading material to engage the sharp edged burr and remove the same, all as will be more fully hereinafter described.

The present invention has for its principal object to provide a new and improved machine of comparatively simple, inexpensive construction which consists primarily of a plurality of rotatable chucks in which the washers are adapted to be engaged, which chucks are mounted on a rotatable turret adapted to be intermittently rotated to bring the chucks and the washers carried thereby into alignment with a rapidly rotated tool shank which carries the flexible disk of abrading material.

Another object of the invention is to provide a new and improved means of simple and inexpensive construction for rotating and indexing the turret head.

A further object is to provide a simple and inexpensive means for simultaneously rotating a plurality of the work chucks at a plurality of work stations.

Another object of the invention is to provide a machine of the character described with a plurality of small compressed air, or electric drills of standard construction, which can be readily mounted upon a tool carrying head; the use of standard small electric, or air drills eliminating the use of complicated gears which otherwise

would be required if the abrasive disk carrying shanks of the machine were driven from the main gearing thereof.

A further object of the invention is to incorporate in a machine of the character described, simple gearing connections between the gearing means for actuating the turret and rotatable chucks carried thereby and the tool carrying head to cause the latter to be reciprocating to and from the tool carrying chucks when the latter are brought by the intermittent rotation of the turret to a position in alignment with the tool carrying heads.

The above and other objects of the invention will appear more fully from the following more detailed description and by reference to the accompanying drawings forming a part hereof, wherein

Fig. 1 is a front, perspective view of a machine constructed in accordance with the present invention;

Fig. 2 is a greatly enlarged central, vertical section through one of the work carrying chucks, the washer to be operated upon showing in full lines the flexible abrading disk when the latter is in its working position and in dotted lines the disc in its raised inoperative position;

Fig. 3 is a horizontal section, partly broken away, taken on the line 3—3 of Fig. 1;

Fig. 4 is a vertical detail taken substantially on the line 4—4 of Fig. 3;

Fig. 5 is a vertical section taken substantially on the line 5—5 of Fig. 3;

Fig. 6 is a plan view of the tool carrying head with the cover thereof removed to illustrate the gearing contained therein;

Fig. 7 is an enlarged detail taken substantially on the line 7—7 of Fig. 6; and

Fig. 8 is a detail of a means for rotating the work chucks.

As hereinbefore explained, the machine of the present invention is particularly designed to remove the burr, formed on a hardened steel washer of special construction, between the bore of the washer at the line of juncture thereof with a curved ground outer face of said washer. The type of operation to be performed can best be understood by reference to the showing of Fig. 2 of the drawings, wherein the numeral 10 indicates the washer, or work piece, which as shown is provided with a bore 11 and a curved outer face 12. These washers which are required to be machined to very accurate and precise finished dimensions, are first rough machined by machine tool cutting operations to within a few thou-

sandths of the required finished size, after which the washers are hardened. The bore 11 is lapped to accurate finished size after which the curved outer face 12 is then ground to finished dimension and contour. As above stated, the grinding of the curved face 12 causes a slight burr to be formed at the line of juncture between said face and the finished bore, which burr may frequently be of smaller diameter than the required finished diameter of the bore 11. It is, therefore, necessary to remove this burr on all of the finished work pieces so that the washer may be placed over the part of the machine on which it is adapted to fit. It is always desirable to remove the burr even though it may not be of less diameter than the required finished size of the bore so as to eliminate the sharp razor-like edge which the burr presents with the consequent danger of cutting the fingers on the hands of the workers required to handle the washers after they have been finished.

As shown in Fig. 2, the washer 10 is placed within a chuck 13 carried in a post 14 and adapted, when the turret hereinafter to be described is intermittently rotated, to bring the washer 12 in alignment with the rotatable shank 15 which carries adjacent to its lower end, a flexible disk of abrading material 16. When the shank 15 is brought downwardly by means presently to be described, the end of the shank enters the bore 11 and causes the flexible disk 16 to be distorted from its substantially flat position to the bowl-like shape shown in full lines to cause the abrasive face of the disk 16 to engage the edge, or burr, formed at the line of juncture between the bore 11 and the ground face 12 of the washer 10, and effectively remove the same.

The machine proper comprises a hollow, cylindrical housing, or base 20, upon the upper end of which is rotatably mounted a turret head 21, which carries a plurality of chuck carrying posts 14 in which the chucks 13 may be either fixedly secured or said chucks may be rotated by means presently to be described. The machine is driven by an electric motor (not shown) mounted within the base 20 of the machine; an electric switch 22 being provided on the outside of the base 20 for control of the motor. The electric motor drives by means of a belt 23, a pulley 24 secured to the end of the main driving shaft 25, to which is keyed a worm 26. The worm 26 meshes with a worm gear 27, suitably keyed to the lower end of a vertical drive shaft 28. At its upper end the shaft 28 carries a sprocket pinion 29 that meshes with a drive chain 30. The drive chain 30 is also trained about a plurality of small sprockets 31, 32, 33 and 34, which are located in position to correspond with the working positions of the chucks around the rear half of the machine when the turret in its intermittent rotation brings the chucks successively under the flexible disks.

As shown in Fig. 3, the turret is provided with eight heads, or chucks, five of which are adapted to be driven, while they are in the working zone in the rear half of the machine, and three of which are not driven as the turret moves into the front loading and unloading zone. The chain 33 also engages with the teeth of a sprocket gear 35 rotatively mounted on a sleeve 36 which passes through the center of a bearing block 37 centrally secured to the turret head 21 (see Fig. 5); suitable anti-friction bearings 38 being interposed between the sleeve 36 and bearing block 37. Suitably secured to the sprocket 35 to rotate there-

with is a pinion 39 that meshes with, and drives, a gear 40. Mounted on the hub 40—a of the gear 40 is a pair of cams 41, 42 which are secured to the gear 40 to rotate therewith by means of one or more bolts or screws 43; the gear 40 and cams 41, 42 forming in effect an unitary rotatable assembly mounted on the upper end of a vertical shaft 44. Carried by this rotatable assembly is a driving pin 45 which projects upwardly beyond the assembly and forms a part of what in effect is a Geneva type of intermittent drive. A small roller 45—a carried by the pin 45 is adapted to engage within one of a plurality of radially extending slots 46 formed in the lower face of a drive plate 47 affixed to and carried by the center block 37 and the turret head 21; there being eight of such slots one for each of the chucks carried by the turret head. As the rotatable assembly consisting of gear 40 and cams 41 and 42 rotates, the small roller 45—a carried by the projecting end of the pin 45 engages within one of the slots 46 and produces a rotation of the turret through one-eighth of a revolution, the pin 45 being so located in the rotatable assembly consisting of the gear 40 and cams 41, 42 as to cause rotation of the turret during approximately 90 degrees of the rotation of the said assembly.

During the 270 degree non-driving rotation of the rotatable assembly, a lock pin 50 carried by a pivoted lever arm 51 is caused to be engaged within one of a plurality of holes 52 provided in a lock plate 53 secured to the bearing block 37 thereby to hold the turret against rotation and with the chucks 13 in proper alignment with the tool heads which carry the flexible abrading disks. The lever arm 51 is pivoted at one end upon a bolt, or stud 53, which in turn is mounted in a boss 54 that projects upwardly from a horizontal web 55 that extends across the upper end thereof. The other end of the lever 51 carries a pin 56 which projects downwardly between the jaws 57 formed in a yoked end of a projecting ear 58 of a lever 59. The lever 59 is pivoted intermediate its ends upon a stud, or pin 60 secured in a boss 70 that projects upwardly from the web 55, the lever 59 resting upon a washer 70—a loosely carried by the pin 60 and interposed between the lower face of the lever 59 and boss 70. The lever 59 carries a pair of cam rollers 71, 72 for engagement with the periphery of the cams 41, 42 respectively.

With the parts of the position as shown in Fig. 3, the roller 72 is shown as engaged with the throw of the cam 42 while the roller 71 is shown as engaged with the dwell of the cam 41. As the rotatable assembly heretofore described rotates in a counterclockwise direction, as indicated by the arrow A in Fig. 3 of the drawings, the roller 72 will ride off the throw portion of the cam 42 just as the roller 45—a carried by the pin 45 begins to engage within a slot 46, the roller 71 simultaneously being engaged by the throw portion 41—a of the cam 41. This causes the lever 59 to be rotated upon its pivot 60, thus causing the pin 56 by its engagement with the jaws 57 of the yoked ear 58 of the lever 59 to move the lever 51 upon its pivot 53 to withdraw the stop pin 50 from the hole 52 with which it had been engaged. As the rotatable assembly continues its rotation in the direction of the arrow A (Fig. 3) the turret 21 will be rotated through one-eighth of a revolution as the pin 45 travels through its circumferential path of movement. Just as the pin 45 and roller 45—a become disengaged from

the slot 46 the roller 71 passes off the throw portion 41-a of the cam 41 while the roller 72 rides up upon the throw portion of the cam 42 to cause the stop pin 50 to be re-engaged within the next one of the holes 52.

During the time the turret is held in the stationary position, the washers 10 carried by the chucks 13 are subjected to the abrading action of the flexible disks 16. These disks, as heretofore pointed out, are carried by a tool shank 15 which is preferably provided at its lower end with a knurled nut 15-a for holding the abrading disks in position upon the tool shank and for readily removing the same when they become worn. As hereinbefore stated the tool shanks are preferably driven by a small standard compressed air or electric motor. In the particular embodiment of the invention illustrated the tool shanks are shown as being driven by small compressed air motors 75 clamped within a split clamping bracket 76 carried by a tool head 77. As shown the machine is provided with three motors 75, each of which is connected by a piece of flexible tubing, or hose 78 with a suitable fitting 79 secured to the top of the head 77 and provided with an inlet pipe 80 adapted to be connected to a source of compressed air. Each of the split brackets 76 is secured, as by a bolt 81, to a vertically adjustable tool carrying head 82, a spring pressed lock pin 83 being provided for engagement within one of a plurality of holes 84 to hold the split bracket 76 in various adjusted angular positions relative to the tool carrying head 82. Each of the tool carrying heads 82 is secured for vertical adjustment by means of a split sleeve type of construction shown most clearly in Fig. 5 and indicated by the reference character 82-a whereby the head 82 and motor 75 may be mounted for vertical adjustment upon a post 85 carried by the head 77. The post 85 projects at its upper end into a suitable bearing support provided in the head 77 and each post 85 is formed with rack gear teeth 86 for engagement by the teeth of a gear 87 encased within the head 77. A plate 88 secured to the outer side wall of the head 77 has formed on it a key 88-a that projects into an elongated keyway 89 formed in the post 85 to hold the same against rotation while permitting vertical sliding movement thereof. The gear 87 is rotatably carried upon a bolt secured in one of the radially extending arms 90 of a spider 91, there being three of such arms 90 one for each of the motors 75. Each gear 87 meshes with a gear 92 carried for rotation upon a bolt, or stud 93, also secured in the spider arm 90. Each gear 92 has suitably secured to it a rack pinion 94, the teeth of which engage with the teeth of a rack 95 formed in a rack head 96 mounted within the tool head 77.

The tool head 77 is supported on, and carried by, the upper end of the tubular shaft 36, which projects through a central hole in the turret 21, the head 77 being supported upon a plate-like extension 98 of a bracket 99, the latter being secured as by set-screws 99-a to the upper end of the tubular shaft 36. The rack head 96 is carried by the upper end of a lift rod 100, the lower end of which projects below the bottom of the sleeve 36 and is provided with cam rollers 101 for engagement with a lift cam 102 secured to the lower end of the shaft 44. The lift cam 102 is provided with a high throw portion 102-a which extends around the cam for approximately an arc of 90 degrees, the throw portion 102 being so located below and relatively to the pin 45 as

to engage the cam roller 101 just before the pin 45 enters one of the slots 46 to rotate the turret and so that the flexible abrading disks 16 and clamping nut 15-a on the end of the tool shank 15 will be lifted clear of the washers 10 just before rotation of the turret starts.

In addition to the high throw portion 102-a, the cam 103 is provided with a plurality of throws 102-b which are of lesser height than the throw 102-a, the purpose of the throws 102-b being to cause the flexible disk 16 to be reciprocated up and down as it is rotated thereby to present new abrading surfaces to the washer and avoid the wearing of a groove in the flexible disk which would otherwise occur if the disk were held in a vertical, stationary position during its rotation.

As hereinbefore pointed out, the chucks 13 which carry the washers 10 may either be held stationary during the engagement of the disks 16 with the washers 10, or the chucks 13 and washers 10 may be rotated during the abrading or polishing operation, in which event the construction shown in Fig. 8 is employed, the chucks 13' being mounted upon the upper end of a stub shaft 110 mounted for rotation in the chuck carrying posts 14', suitable anti-friction bearings 111 preferably being interposed between the shaft 110 and chuck carrying post. Secured to the lower end of the shaft 110 is a gear 112 which is adapted, when the turret is brought to one of its locked, stop positions, to engage with a gear 113 carried by the upper end of a second stub shaft 114 and which at its lower end has secured to it one of the sprockets 29, 31, 32, 33 or 34, as the case may be. As each of these sprockets 29 to 34 inclusive are driven by the chain 39, obviously rotation of the chucks and the part carried thereby will result.

The manner in which the machine operates should be fully apparent from the foregoing description but for clarity the following brief description of the complete operation of the machine is given. Assuming that the switch 22 is actuated to cause the driving motor of the machine to rotate the pulley 24, rotation of such pulley is of course communicated through worm 26, worm wheel 27 and shaft 28 to the sprocket pinion 29. As the sprocket 29 rotates it will drive the chain 39 which in turn produces rotation of the central sprocket 35 and the gear 39 which is attached to it. Rotation of the gear 39 is communicated to the gear 40, shaft 44 and the rotatable assembly consisting in addition to the gear 40 of the two cams 41, 42. Let it be assumed that the compressed air motors 75 have been set in rotation by the opening of a valve (not shown) in the compressed air line leading to the inlet pipe 80 or by the actuation of suitable valves on each individual motor; the rotation of the motor 75 having been commenced before the switch 22 is cut in. Let it also be assumed that the parts are substantially in the position shown in Fig. 3 of the drawings, with the lock pin 50 in engagement with one of the holes 52 of the lock plate 73. As the pin 45 moves towards the slot 46 in the driving plate 47 which lies in the path of movement of said pin, the cam roller 72 will ride off the throw of the cam 42 shortly before the pin reaches said slot 46. Immediately thereafter, and just as the pin 45 is adapted to engage within the said slot 46, the cam roller 71 is engaged by the throw portion 41-a of the cam 41, thus withdrawing the lock pin 50 from the hole 52 with which it had been engaged. Substantially simultaneously with this action the

high throw 102—a of cam 102 engages with the roller 101 on the bottom of the lift rod 100 causing the latter to be moved vertically upward. The upward movement of lift rod 100 is communicated by rack 95, rack pinion 94 and gears 92 and 87 to the rack gear teeth 86 formed on the upper end of post 85, thus causing the post 85 to be raised and carry along with it the tool carrying head 82, the clamping bracket 76 and the compressed air motor 75. This raises the lower end of the tool shank 15 to an extent sufficient to clear the washer 10 as indicated in the dotted line showing in Fig. 2.

When the pin 45 enters into slot 46, it will cause the drive plate 47 to be rotated, thus producing rotation of the bearing block 37 and the turret 21 causing the latter to be rotated through one-eighth of a revolution and to bring three of the chucks in correct alignment with the three compressed air motors 75 and the flexible disks driven thereby. Just as the roller 45 passes out of the slot 46 which it has moved from the right side to the left side of the vertical center line passing through the axis of rotation of the turret, as shown in Fig. 3, the cam roller 72 rides off the dwell portion of the cam 42 into the throw portion thereof while the cam roller 41 rides off the throw portion 41—a of the cam 41 into the dwell portion thereof. This causes the lever 49 to be rotated in a counter-clockwise direction (Fig. 3) and causes the jaws 57 formed in the yoked ear 58 of the lever 59 to move the pin 56 secured to the lever 51 to move the said lever 51 upon its pivot 53 in a clockwise direction (Fig. 3) to push the stop pin 59 into engagement with the next hole 52 of the stop plate 73. The turret 21 now being held in a stationary locked position with three of the chucks 13 in vertical alignment with the three compressed air motors 75, the disks 16 are caused to be lowered into engagement with the washer 10 as indicated in full lines in Fig. 2 of the drawings because of the fact that the roller 101 of the lift rod rides off the high throw portion 102—a of the cam 102. The successive plurality of the lesser throws, or nodes 102—b of the cam then engage the roller 101 and cause the lift rod 100 to be moved comparatively slowly up and down and communicate its vertical movements to the compressed air motors, the tool shanks 15 and the disks carried thereby, until the roller 101 again rides up on the high throw 102—a of the cam 102 to raise the disks clear of the washer after which the turret is again rotated through one-eighth of a revolution as above described.

It will of course be understood that the number of motors 75 with which the machine is provided may obviously be varied, and likewise the position of such motors may readily be changed. For example, the motor 75 and disk 16 carried thereby shown at the rear end of the machine might be dispensed with and both front and rear portions of the machine used for loading and unloading, or it is perfectly obvious that the tool carrying head might be provided with two motors 75 on each of the posts 85 with but very slight modification of the motor carrying brackets and so that the washers carried by two adjacent chucks would be subjected to the abrading operation.

It will likewise be understood that although the drawings show, and the foregoing specification describes, an embodiment of the invention that has proven highly successful in actual commercial operation, many changes, variations and

modifications in the constructional details of such embodiment may be resorted to without departing from the spirit of the invention as set forth in the claims hereunto appended.

5 I claim:

1. In a machine of the character described, a rotatable turret, a plurality of work carrying chucks carried thereby, a tool carrying head mounted in juxtaposition to said turret, a plurality of rotatable abrading tools carried by said head each consisting of a flexible disk of abrading material, means for intermittently rotating said turret to bring said chucks into alignment with said abrading tools, means for reciprocating said abrading tools during the rotation thereof to bring said flexible disks into engagement with the bore of a work piece carried by said chucks to thrust said flexible disks into said bore and including means for reciprocating said tools to continuously change the line of contacting engagement of said disk with the work piece during an abrading operation.

2. In a machine of the character described, a rotatable turret, a plurality of work carrying chucks carried thereby, a tool carrying head fixedly mounted in juxtaposition to said turret, an individual self-contained rotary motor carried by said head, a flexible disk of abrading material carried by said motor, intermittent driving means for rotating said turret to bring said chucks successively into alignment with said disk of abrading material, cam means connected with said intermittent driving means and means for causing reciprocation of said motor and disk relative to said tool carrying head and said turret to bring said flexible disks into engagement with the bore of a work piece carried by said chucks.

3. In a machine of the character described, a rotatable turret, a plurality of work carrying chucks carried thereby, a tool carrying head fixedly mounted in juxtaposition to said turret, an individual self-contained rotary motor carried by said head, a flexible disk of abrading material carried by said motor, intermittent driving means for rotating said turret to bring said chucks successively into alignment with said disk of abrading material, cam means connected with said intermittent driving means, means for causing reciprocation of said motor and disk relative to said tool carrying head and said turret to bring said flexible disk into engagement with the bore of a work piece carried by said chucks, including a rack bar actuated by said cam means and a second rack bar upon which said motor is adjustably mounted and gearing carried by said tool carrying head and interposed between said rack bars.

4. A machine as set forth in claim 3 in which said cam means includes a cam throw portion for moving said disk of abrading material into and out of engagement with the work piece carried by said chuck and a plurality of cam throws of lesser amplitude than said first named cam throw to cause the flexible disk to be reciprocated slowly relative to said work piece during the rotating engagement of said disk with said work piece.

5. In a machine of the character described, a rotatable turret, a plurality of work carrying chucks carried thereby, a tool carrying head mounted in juxtaposition to said turret, a plurality of rotatable abrading tools carried by said head each consisting of a flexible disk of abrading material, means for intermittently rotating said turret to bring said chucks into alignment with said abrading tools, means for rotating said chucks comprising a plurality of chain sprockets

located at spaced intervals substantially in alignment with said abrading tools, a single driving chain trained upon said sprockets, a driving spur pinion connected with, and driven by, each of said sprockets, and each of said work chucks being provided with a spur gear adapted to be brought into driving engagement with one of said driving spur pinions to be rotated thereby when said chucks during the intermittent rotation of said turret are brought into alignment with said abrading tools.

6. In a machine of the character described a fixed supporting base, a driving gearing carried thereby, a turret mounted for rotation upon said base, a plurality of work carrying chucks carried by said turret, a tool carrying head fixedly mounted in juxtaposition to said turret, a plurality of rotatable abrading tools carried by said tool head each consisting of a flexible disk of abrading material arranged in spaced relationship about said tool head, an intermittent driving mechanism interposed between said gearing and said turret for rotating said turret to bring said chucks into alignment with said abrading tools, stop means for holding said turret against rotation when said chucks are brought into alignment with said abrading tools, cam means secured to, and rotating in unison with said intermittent driving means to cause said abrading tools to be moved into and out of engagement with a work piece carried by said chucks during the rotation of said turret and to hold said abrading disks in reciprocating contacting operative engagement with said work piece when said turret is held against movement.

7. In a machine of the character described a fixed supporting base, a driving gearing carried thereby, a turret mounted for rotation upon said base, a plurality of work carrying chucks carried by said turret, a tool carrying head fixedly mounted in juxtaposition to said turret, a plurality of rotatable abrading tools carried by said tool head each consisting of a flexible disk of abrading material arranged in spaced relationship about said tool head, an intermittent driving mechanism interposed between said gearing and said turret for rotating said turret to bring said chucks into alignment with said abrading tools, stop means for holding said turret against rotation when said chucks are brought into alignment with said abrading tools, cam means secured to, and rotating in unison with said intermittent driving means to cause said abrading tools to be moved into and out of engagement with a work piece carried by said chucks during the rotation of said turret and to hold said abrading disks in contacting operative engagement with said work piece when said turret is held against movement, said stop means comprising a stop plate secured to said turret provided with a plurality of spaced holes, a pair of pivoted levers mounted adjacent said stop plate, a stop pin carried by one of said levers, and cam means associated with said intermittent driving means to cause said stop pin to be engaged within one of said holes to prevent movement of said turret when said turret is not being rotated by said intermittent driving means and for disengaging said stop pin during the periods of rotation of said turret.

8. In a machine of the character described a fixed supporting base, a driving gearing carried thereby, a turret mounted for rotation upon said base, a plurality of work carrying chucks carried by said turret, a tool carrying head fixedly mounted in juxtaposition to said turret, a plural-

ity of rotatable abrading tools carried by said tool head each consisting of a flexible disk of abrading material arranged in spaced relationship about said tool head, an intermittent driving mechanism interposed between said gearing and said turret for rotating said turret to bring said chucks into alignment with said abrading tools, stop means for holding said turret against rotation when said chucks are brought into alignment with said abrading tools, cam means secured to, and rotating in unison with said intermittent driving means to cause said abrading tools to be moved into and out of engagement with a work piece carried by said chucks during the rotation of said turret and to hold said abrading disks in contacting operative engagement with said work piece when said turret is held against movement, said stop means comprising a stop plate secured to said turret provided with a plurality of spaced holes, a pair of pivoted levers mounted adjacent said stop plate, a stop pin carried by one of said levers, cam means associated with said intermittent driving means to cause said stop pin to be engaged within one of said holes to prevent movement of said turret when said turret is not being rotated by said intermittent driving means and for disengaging said stop pin during the periods of rotation of said turret and additional cam means associated with said intermittent driving mechanism for causing said flexible abrading disks to be moved into engagement with the work piece carried by said chucks when said stop pin is engaged with one of the holes of said stop plate.

9. In a machine of the character described a fixed supporting base, a driving gearing carried thereby, a turret mounted for rotation upon said base, a plurality of work carrying chucks carried by said turret, a tool carrying head fixedly mounted in juxtaposition to said turret, a plurality of rotatable abrading tools carried by said tool head each consisting of a flexible disk of abrading material arranged in spaced relationship about said tool head, an intermittent driving mechanism interposed between said gearing and said turret for rotating said turret to bring said chucks into alignment with said abrading tools, stop means for holding said turret against rotation when said chucks are brought into alignment with said abrading tools, cam means secured to, and rotating in unison with, said intermittent driving means to cause said abrading tools to be moved into and out of engagement with a work piece carried by said chucks during the rotation of said turret and to hold said abrading disks in contacting operative engagement with said work piece when said turret is held against movement, said stop means comprising a stop plate secured to said turret provided with a plurality of spaced holes, a pair of pivoted levers mounted adjacent said stop plate, a stop pin carried by one of said levers and cam means arranged with said intermittent driving means to cause said stop pin to be engaged within one of said holes to prevent movement of said turret when said turret is not being rotated by said intermittent driving means and for disengaging said stop pin during the periods of rotation of said turret and additional cam means associated with said intermittent driving mechanism for causing said flexible abrading disks to be moved into engagement with the work piece carried by said chucks when said stop pin is engaged with one of the holes of said stop plate, including means for causing said flexible disks to be recip-

rocated slowly relative to said work piece during said period.

10. In a machine of the character described, a fixed supporting base, a driving gearing carried thereby, a turret mounted for rotation upon said base, a plurality of work carrying chucks carried by said turret, a tool carrying head fixedly mounted in juxtaposition to said turret, a plurality of rotatable abrading tools carried by said tool head each consisting of a flexible disk of abrading material arranged in spaced relationship about said tool head, an intermittent driving mechanism interposed between said gearing and said turret for rotating said turret to bring said chucks into alignment with said abrading tools, stop means for holding said turret against rotation when said chucks are brought into alignment with said abrading tools, cam means secured to, and rotating in unison with said intermittent driving means to cause said abrading tools to be moved into and out of engagement with a work piece carried by said chucks during the rotation of said turret and to hold said abrading disks in contacting operative engagement with said work piece when said turret is held against movement, said stop means comprising a stop plate secured to said turret provided with a plurality of spaced holes, a pair of pivoted levers mounted adjacent

said stop plate, a stop pin carried by one of said levers and cam means arranged with said intermittent driving means to cause said stop pin to be engaged within one of said holes to prevent movement of said turret when said turret is not being rotated by said intermittent driving means and for disengaging said stop pin during the periods of rotation of said turret, additional cam means associated with said intermittent driving mechanism for causing said flexible abrading disks to be moved into engagement with the work piece carried by said chucks when said stop pin is engaged with one of the holes of said stop plate, including means for causing said flexible disks to be reciprocated slowly relative to said work piece during said period, and gearing means interposed between said last mentioned cam means and said flexible abrading disks comprising a pair of spaced rack bars carried by said tool head and gearing interposed between said rack bars, one of said rack bars being provided with an anti-friction roller for engagement by said last mentioned cam means and an individual self-contained motor to which said flexible abrading disk is attached carried by the other of said rack bars.

GUSTAVE A. CARLSON.
